DISPENSING DEVICEAndrew B. Karn, 420 E. 86th St., New York, N.Y.
Filed Jan. 14, 1963, Ser. No. 251,385
18 Claims. (Cl. 156—247)

The present invention relates to tape dispensing devices, and, more particularly, to novel and improved methods and apparatus for dispensing tape having a plurality of separable layers, one of which is waste, and for applying a release-type pressure-sensitive adhesive from a transfer tape to a surface to be coated.

Various techniques and devices have been developed for dispensing or applying adhesive and the like, such as that disclosed in Patent No. 2,845,041, granted to A. B. Karn on July 29, 1958, wherein an adhesive applicator device applies an adhesive releasably affixed to a backing tape to a surface. In the various embodiments disclosed in that patent, for example, the tape, commonly referred to as a "transfer tape," is forced against a surface by a rotatable feed roller. The rotation of the feed roller either directly or through a mechanical chain drive, feeds the waste tape backing or body onto a take-up spool, or into a storage chamber, or outwardly of the dispenser housing.

In each of the embodiments of Patent No. 2,845,041 and other known devices, the operation of the devices hinges upon the proper functioning of a plurality of moving elements, some of which are driven by various types of drive mechanisms, which render the device more costly and more complicated in manufacture, assembly, and use than is acceptable for general use as an over-the-counter item.

In accordance with the novel and improved methods and apparatus of the invention, the dispensing and application of transfer tape and the like is accomplished by apparatus employing no moving parts, and having a very simplified housing including a fixed mandrel, a fixed tape engaging means, and a fixed guide means, which is susceptible of being readily manufactured, assembled with and used for dispensing tape having a plurality of separable layers from a roll. In one embodiment, adhesive may be applied to an appropriate surface by merely pushing the applicator across the surface so that the adhesive is stripped from the transfer tape liner to which it is relatively lightly bonded and transferred to the surface to be coated, the waste liner being automatically fed through a guide channel for disposal and separation from adjacent layers of unused tape. In other embodiments of the invention, a tape having adhesive on one or both sides of a coated paper liner, which may be separated from a waste liner, may be used in the dispenser, and either applied directly to a surface or fed from the dispenser for later application to such a surface. In all of the embodiments, the waste liner is separated from the adhesive or tape and guided in the dispenser to an appropriate location for disposal.

For a more complete understanding of the invention, reference may be had to the following detailed description taken in conjunction with the accompanying figures of the drawings, in which:

FIGURE 1 is a side elevational view of an exemplary embodiment of a tape dispensing device;

FIG. 2 is a side elevational view of the cover for the tape dispensing device of FIG. 1;

FIG. 3 is an end view of the cover of FIG. 2;

FIG. 4 is a side elevational view in section of an alternate embodiment of a tape dispensing device, in accordance with the invention;

FIG. 5 is an end view of the tape dispensing device of FIG. 4;

2

FIG. 6 is a partial sectional view of an alternate embodiment of a braking means, in accordance with the invention;

FIG. 7 is a partial sectional view of another alternate embodiment of a braking means, in accordance with the invention;

FIG. 8 is a partial side elevational view of a further alternate embodiment of the invention, showing means for compensating for substantial changes in the diameter of the tape roll;

FIG. 9 is a side elevational view of a still further exemplary embodiment of the invention; and

FIG. 10 is a schematic side elevational view of still another embodiment of the invention having a modified form of guide means.

In FIG. 1, a roll of transfer tape 10, having a conventional core 11, is mounted on a hollow mandrel 12, formed integrally with or mounted on a generally circular housing 13, which may be formed, for example, of any suitable conventional plastic material. The roll of tape 10 and its core 11 are adapted to rotate about the mandrel 12 during withdrawal of tape therefrom. The roll of tape 10 comprises a tape wound about the core 11 having at least two separable layers, including a waste liner 14 and an adhesive 15, mounted on and radially outward of the waste liner 14. The liner 14 may consist of any suitable flexible material such as, for example, Holland cloth or glassine, with a suitable conventional release coating, if desired, separating the liner 14 from the adhesive 15, which may be a suitable ever-tacky gum or a web-reinforced ever-tacky gum, the materials of the liner 14 and the adhesive 15 being so chosen as to have only slight affinity.

The housing 13 is shown as being formed in two complimentary sections including a back plate 16 (FIG. 1) and a cover plate 17 (FIG. 2) with respective mating flanges 18 and 19.

A peripherally exposed tape engaging means or applicator 20 having a rounded outer surface extend slightly beyond the back plate 16 and the cover plate 17, when the housing 13 is assembled, is formed integrally with or otherwise suitably mounted on the back plate 16. The tape engaging means 20 is in the form of a hollow cylinder, similar to the mandrel 12, each being adapted to receive respective studs 21 and 22, which are formed integrally with or mounted on the cover plate 17.

A flange 18 extends peripherally along a portion of the back plate 16 and then inwardly thereof in a generally circular manner with a rounded outwardly hooked shaped extremity 24 forming a portion of a guide means 25. An additional flange 26 is mounted peripherally on the back plate 16 and extends along and substantially parallel to that portion of the flange 18 leading to the hooked shaped member 24 to form a disposal chamber 27. One extremity of the flange 26 approaches, but is spaced from, the flange 18 to form an external opening to the disposal chamber 27. The other extremity 28 of the flange 26 curves inwardly on the back plate 16 about the hooked shaped member 24, but in spaced-apart relation thereto, to form a channel or guide path leading into the disposal chamber 27, and constitutes a second element of the guide means 25.

A third element of the guide means 25 comprises an upstanding post or parting stud 29 spaced outwardly of a tangential projection from the maximum circumferential portion of the roll of tape 10 to the rounded tape engaging means 20, and is spaced apart from the hooked shaped member 24 and the flange portion 28 a distance sufficient to form therewith respective guide channels or paths.

The flange 19 on the cover plate 17 is formed in two sections which overlie and mate with the peripheral portions of flanges 18 and 26 on the back plate 16, with an opening provided from the disposal chamber 27.

In assembly, the roll of tape 10 is placed about the mandrel 12 and a lead portion of the tape is withdrawn and passed through the guide means 25, in a path between the post 29 and the hooked shaped member 24 and the post 29 and the extension 28, around the tape engaging means 20 and with its liner 14 in overlying relation and in frictional engagement with a circumferential portion of the roll 10. The liner 14 continues around the roll 10 and passes therefrom in a path adjacent a portion of the tape extending from the roll 10 to the guide means 25, and thence on a path through the guide means 25 between the post 29 and the hooked shaped member 24, and then between the extension 28 and the hooked shaped member 24 into the disposal chamber 27 and outwardly therefrom. That portion of the tape leading beyond the tape engaging means 20, on original assembly, preferably consists of the waste liner 14 without any adhesive 15.

In use, the tape engaging means 20 and the adjoining tape is placed adjacent a surface 30, which is to be coated. External pressure is either manually or mechanically placed upon the housing 13 to force the tape engaging means 20 against the surface 30 and push the entire housing in the direction of the arrow along the surface to be coated. The pressure exerted by the housing 13 and its fixed tape engaging means 20 upon the tape causes the release-type pressure-sensitive adhesive to coat the surface 30. The waste liner 14 is then separated from the transferred adhesive 15 and is drawn over the roll 10 by the driving relation established through the closed belt surrounding both the roll 10 and the rounded tape engaging means 20. This driving relation causes a controlled rotation of the roll 10 about the mandrel 12, feeding new tape, including the adhesive 15, through the guide means 25, where it is separated from the previously exhausted waste liner 14 by being drawn in a path toward the tape engaging means 20 from the post 29 at an angle to its path from the circumference of the roll 10 to the post 29. The flange 18 serves to guide the leading portion of the waste liner 14 into the guide means 25 during original assembly, in the event that the leading portion of waste liner 14 is not pressed into full contact with the circumferential portion of roll 10 by the operator. The parting stud or post 29 provides a fixed axis, in definite spatial relationship to the other elements 24 and 28 of the guide means 25, about which the tape and the overlying waste liner may be separated and induced into separate paths. The elements 24 and 28 of the guide means 25 provide a relatively gently curved channel through which the exhausted waste liner 14 is pushed by means of the driving relation of the closed belt of tape.

The member 24 of the guide means 25 also provides thrust upon the waste liner 14, thereby maintaining it in frictional contact with the underlying section of tape as the waste liner is pushed through the guide means 25, and when the leading portion of the waste liner 14 is torn off, after it has been discharged from the disposal chamber 27. Thrust is also provided by the flange 26 and its curved extension 28, as they maintain the waste liner 14 in a curved path.

A feature of this embodiment, in which the parting stud is located outwardly from a line tangential to the maximum outer circumference of the tape roll 10 and the rounded tape engaging means and applicator 20, is that it is "self-threading"—that is, during original assembly, once the leading portion of the waste liner 14, which emanates from the applicator 20, has been placed into frictional engagement with a circumferential portion of the roll 10, the waste liner 14 will, without further handling, be automatically guided through the guide

means 25 and lead out of the dispenser, as it is used to dispense adhesive.

In some cases, the chamber 27 may be normally closed to store the exhausted waste liner 14 in any suitable manner. A conventional cutting edge may be formed on the extremity of the flange 26 to facilitate cutting off portions of exhausted waste liner.

When the dispensing device is being withdrawn from the surface 30, thereby breaking the adhesive 15, it is desirable when the adhesive is of a type having appreciable tensile strength to brake the withdrawal of tape from the roll 10. In the embodiment of FIGS. 4 and 5, the housing 13' has a side wall 36 including therein a flexible braking flange 37, which may be manually pressed inwardly of the housing 13' against the exhausted waste liner 35 and a new section of a transfer tape 38, and a brake 39 mounted on or formed integrally with the housing 13' at a point intermediate a roll of tape 40 and a guide means 41, but preferably outwardly of a tangential projection therebetween. Pressure of the braking flange 37 against the tape 38 and the brake plate 39 brakes the withdrawal of tape from the roll 40. The structural details of the embodiment of FIGS. 4 and 5 may be otherwise similar to that of FIG. 1, in that there is a closed belt driving relation involving the roll of tape 40 and a fixed tape engaging means or applicator 42.

FIG. 4 also illustrates a variation of the guide means whereby the waste liner is angularly displaced from the plane which contains the tape roll and tape and is conducted externally of the dispenser through an opening 45 in the back plate 43. This displacement may be achieved by appropriately canting the curved element 44.

In FIG. 6, the flexible braking flange 37' has an enlarged extremity 46 adapted to force the tape 38' into a hollow 47 in a brake plate 48.

In the embodiment of FIG. 7, the braking action is accomplished by manual insertion of a finger through an aperture in the housing 51 of the dispenser against the tape 52 as it passes over a brake post 53 formed in the housing.

When using rolls of tape where there is a large differential between the maximum diameter of the tape roll and the diameter of the core when the tape is exhausted, the guiding function of a flange 64 (FIG. 8) may be augmented by positioning a suitably curved guide flange 61 on the housing of the dispenser at a point intermediate a roll of tape 62 and a guide means 63 outwardly of a tangential projection drawn from the maximum circumferential extent of the roll 62 to the guide means 63, thereby fixing the direction of movement or path of the tape from the roll 62 as it approaches the guide means 63 independently of the diameter of the roll of tape at any time during its use. It is noted that this function is also provided by the brake plates 39, 48, and 53 of FIGS. 4, 6 and 7.

In the embodiment of FIG. 9, a guide means 71, which functions similarly to the guide means of the other embodiments, is positioned on the housing at a point relative to a tape engaging or applicator means 72, whereby a roll of tape 73 is interposed in the path from the guide means 71 to the tape engaging means 72. This embodiment functions similarly to the other embodiments, with the exception that the tape 74 being withdrawn from the roll 73, after separation from the exhausted waste liner at the guide means, passes in overlying relation and in frictional engagement with the roll 73 for at least an additional circumferential extent. The purpose of positioning the guide means in this manner, close to the trailing edge of the dispenser, is to facilitate the passage of waste liner over the hand which holds the dispenser.

FIG. 10 illustrates an embodiment in which a rounded tape engaging means 91 comprises an element of the guide means 92, by incorporating the functions of the parting stud 29 (FIG. 1) in addition to its tape applying function. This embodiment has the advantage of some-

what simplified construction. However, since the other elements 93 and 94 of the guide means 92 are located in close proximity of the tape engaging means 91, the operator's view of the surface 95 to which the adhesive layer is affixed is somewhat obstructed.

Thus there has been provided, in accordance with the invention, novel and improved tape or adhesive dispensing methods and apparatus of a greatly simplified nature, employing no moving parts, which are susceptible of utilization in a wide variety of applications.

It will be obvious to those working in the art that the above-described embodiments and methods of use are meant to be merely exemplary, and that they are susceptible of modification and variation without departing from the spirit and scope of the invention. For example, the dispenser may be used with a saturated tissue reinforced type of transfer tape or a tape having adhesive on one or both sides of a coated paper liner, which is to be separated from an additional waste liner, the coated paper liner and adhesive being applied directly to a surface or merely withdrawn from the dispenser across the tape engaging means for later application to a surface. Also, in some instances it may be desirable to use a rotatable applicator or tape engaging means instead of a fixed applicator. Therefore, the invention is not deemed to be limited except as defined by the appended claims.

I claim:

1. A method of dispensing a release-type pressure-sensitive adhesive from a roll of tape including a waste liner and a release-type pressure-sensitive adhesive releasably mounted on and radially outward of the liner with respect to contiguous portions thereof in the roll, comprising withdrawing a lead portion of said tape; pressing said tape against a surface zone and advancing said roll relative to a surface to apply the adhesive thereto and separate it from said waste liner; passing said waste liner at least partially around and in overlying relation to and in engagement and driving relation with a circumferential portion of the roll, passing said waste liner and the underlying tape through a path having a fixed portion spaced radially outward from the periphery of said roll and separating said waste liner from said underlying tape at said portion and directing it away from said zone and roll.

2. A tape dispensing device for dispensing tape having a plurality of separable layers wound in a roll, comprising a housing, a mandrel mounted on said housing adapted to rotatably support a tape roll during withdrawal of tape therefrom, a rounded tape engaging means for engaging one layer of the tape withdrawn from the tape roll and applying another layer thereof to a surface, said one layer being diverted into contact with and superimposed on the outermost tape on said roll and extending around a substantial portion of the periphery of said roll, said tape engaging means being mounted on said housing and spaced apart from the center of said mandrel a distance greater than one-half the maximum diameter of the tape roll to be used in the dispensing device, and guide means mounted on said housing and positioned outside an area defined by the maximum circumferential extent of the tape roll for deflecting said tape and said one superimposed layer out of contact with said roll and including discharge means for separating said one superimposed layer from said deflected tape and directing said separated one layer of said tape in a path away from said rounded tape engaging means.

3. A device as claimed in claim 2, including means on said housing to facilitate braking the withdrawal of tape from the tape roll.

4. A tape dispensing device for dispensing tape having a plurality of separable layers wound in a roll, comprising a housing, a mandrel mounted on said housing adapted to rotatably support a tape roll during withdrawal of tape therefrom, a rounded tape engaging means for engaging one layer of the tape withdrawn from the tape roll and applying another layer thereof to a surface, said one layer

being diverted into contact with and superimposed on the outermost tape on said roll and extending around a substantial portion of the periphery of said roll, said tape engaging means being mounted on said housing and spaced apart from the center of said mandrel a distance greater than one-half the maximum diameter of the tape roll to be used in the dispensing device, and guide means mounted on said housing and positioned outside an area defined by the maximum circumferential extent of the tape roll and by tangential projections from said maximum circumferential extent to said rounded tape engaging means for deflecting said tape and said one superimposed layer out of contact with said roll and including discharge means for separating said one superimposed layer from said deflected tape and directing said separated one layer of the tape in a path away from said rounded tape engaging means.

5. A tape dispensing device for dispensing tape having a plurality of separable layers wound in a roll, comprising a housing, a mandrel mounted on said housing adapted to rotatably support a tape roll during withdrawal of tape therefrom, a rounded tape engaging means for engaging one layer of the tape withdrawn from the tape roll, said tape engaging means being mounted on said housing and spaced apart from the center of said mandrel a distance greater than one-half the maximum diameter of the tape roll to be used in the dispensing device, and guide means adapted to receive said superimposed one layer and said outermost tape fixedly mounted on said housing and positioned outside an area defined by the maximum circumferential extent of the tape roll to be used and by tangential projections from said maximum circumferential extent to said rounded tape engaging means for deflecting said tape and said one superimposed layer out of contact with said roll and including discharge means for separating said one superimposed layer from said deflected tape and directing the separated layer of the tape in a path away from said rounded tape engaging means and directing the unseparated portion of the tape in a path angularly displaced from the path of the separated layer toward said rounded tape engaging means.

6. A tape dispensing device for dispensing tape having a plurality of separable layers, one of which is a waste liner, wound in a roll, comprising a housing, a mandrel mounted on said housing adapted to rotatably support a tape roll during withdrawal of tape therefrom, a rounded tape engaging means for engaging the waste liner of the tape withdrawn from the tape roll and applying another layer thereof to a surface, said waste liner being diverted into contact with and superimposed on the outermost tape on said roll and extending around a substantial portion of the periphery of said roll, said tape engaging means being mounted on said housing and spaced apart from the center of said mandrel a distance greater than one-half the maximum diameter of the tape roll to be used in the dispensing device, first guide means adapted to receive the waste liner and an adjacent portion of unseparated tape fixedly mounted on said housing and positioned outside an area defined by the maximum circumferential extent of the tape roll for deflecting said tape and said waste liner superimposed thereon out of contact with said roll and including discharge means for separating said waste liner from said deflected tape and directing the waste liner in a path away from said rounded tape engaging means and directing the unseparated portion of the tape in a path angularly displaced from the path of the waste liner toward said rounded tape engaging means, and second guide means fixedly mounted on said housing at a point outside the area defined by the maximum circumferential extent of the tape roll and intermediate the point of withdrawal of tape from the tape roll and said first guide means for directing tape from the tape roll to said first guide means in a path independent of the circumferential extent of the tape roll during withdrawal of tape therefrom.

7. A tape dispensing device as claimed in claim 6, wherein said first guide means is positioned adjacent a tangential projection from said second guide means to said rounded tape engaging means.

8. A tape dispensing device as claimed in claim 6, wherein said first guide means is positioned outwardly of a tangential projection from said second guide means to said rounded tape engaging means.

9. A tape dispensing device for dispensing tape having a plurality of separable layers wound in a roll, comprising a housing, a mandrel mounted on said housing adapted to rotatably support a tape roll during withdrawal of tape therefrom, a rounded tape engaging means adapted to engage one layer of the tape and to urge the tape into contact with a surface on which at least a separable layer of the tape is to be applied in response to external pressure exerted on said housing, said one layer being diverted into contact with and superimposed on the outermost tape on said roll and extending around a substantial portion of the periphery of said roll, said tape engaging means being mounted on said housing and spaced apart from the center of said mandrel a distance greater than one-half the maximum diameter of the tape roll to be used in the dispensing device, and guide means fixedly mounted on said housing and positioned outside an area defined by the maximum circumferential extent of the tape roll to be used and by tangential projections from said maximum circumferential extent to said rounded tape engaging means for deflecting said tape and said one superimposed layer out of contact with said roll and including discharge means for separating said one layer from said deflected tape and directing said one layer of the tape in a path away from said rounded tape engaging means.

10. A dispenser for a roll of transfer tape having a plurality of layers including a waste liner and a release-type pressure-sensitive adhesive releasably mounted on and radially outward of the liner with respect to respective contiguous portions of the liner in said roll, comprising a housing, a mandrel mounted on said housing for rotatably supporting the roll of transfer tape during withdrawal of tape therefrom, a peripherally exposed fixed rounded applicator mounted on said housing in spaced-apart relation to the center of said mandrel by a distance greater than one-half the maximum diameter of the roll of transfer tape for slidably engaging the waste liner of the transfer tape and supporting the transfer tape adjacent the surface to which the pressure-sensitive adhesive is to be secured in response to external pressure exerted on said housing, the liner of the transfer tape passing from the periphery of the roll when mounted on said mandrel around said applicator and in overlying relation to and in circumferential engagement with a substantial extent of a circumferential portion of the roll to form a continuous driving relation whereby movement of the liner about said rounded applicator induced by movement of said applicator across the surface to which the adhesive portion of the tape is to be secured draws the liner bearing adhesive from the roll to the point of application and leads the liner after the adhesive is separated therefrom back over the circumferential portion of the roll, and guide means positioned outwardly from a line tangential to the maximum outer circumference of the roll of transfer tape and said rounded applicator for deflecting said tape and said one superimposed layer out of contact with said roll and including discharge means for separating said one layer from said deflected tape and directing it outwardly therefrom.

11. A tape dispensing device, comprising a roll of transfer tape, said tape having a plurality of layers including a waste liner and a release-type pressure-sensitive adhesive releasably mounted on and radially outward of said liner with respect to respective contiguous portions thereof in said roll, a housing, a mandrel mounted on said housing for rotatably supporting said roll during withdrawal of

5 said roll for slidably engaging said waste liner and supporting said tape adjacent a surface to which said pressure-sensitive adhesive is to be secured in response to external pressure exerted on said housing, said waste liner being diverted into contact with and superimposed on the outermost tape on said roll and extending around a substantial portion of the periphery of said roll, guide means fixedly mounted on said housing and positioned outside an area defined by the maximum circumferential extent of said roll for providing a first path leading toward said applicator at an angle to the path of said tape leading to said guide means and a second path leading away from both said applicator and said roll, a portion of said tape including both said liner and said adhesive extending from said roll to said guide means and then along said 10 first path to and at least partly around said applicator for deflecting said tape and said waste liner superimposed thereon out of contact with said roll and including discharge means for separating said waste liner from said deflected tape in a path away from said applicator.

15 20 25 12. A device as claimed in claim 11, including means in said housing for facilitating braking of the movement of said tape.

13. A tape dispensing device for dispensing tape having a plurality of separable layers, one of which is a waste liner wound in a roll, comprising a housing, a mandrel mounted on said housing adapted to rotatably support a tape roll during withdrawal of tape therefrom, first guide means fixedly mounted on said housing and positioned outside an area defined by the maximum circumferential extent of the tape roll adapted to receive the waste liner and an adjacent unseparated portion of the tape for separating the waste liner and the adjacent unseparated portion of tape and directing the waste liner in a path away from a dispensing point and directing 30 35 40 45 the adjacent unseparated tape in a path angularly displaced from the path of the waste liner toward said dispensing point, and second guide means fixedly mounted on said housing at a point outside the area defined by the maximum circumferential extent of the tape roll and intermediate the point of withdrawal of tape from the tape roll and said first guide means for directing tape from the tape roll to said first guide means in a path independent of the circumferential extent of the tape roll during withdrawal of tape therefrom.

14. A tape dispensing device for dispensing tape having a plurality of separable layers wound in a roll, said device comprising a housing, a mandrel mounted on said housing adapted to rotatably support a tape roll during withdrawal of tape therefrom, a rounded tape engaging means for engaging a layer of the tape withdrawn from the tape roll, said tape engaging means being mounted on said housing in spaced relation to said mandrel, and guide means adapted to receive a previously separated layer of tape and an adjacent portion of unseparated tape 55 60 65 mounted on said housing in spaced relation to said mandrel for separating the separated layer from the adjacent unseparated portion of the tape and directing the separated layer of the tape in a path away from said rounded tape engaging means and directing the unseparated portion of the tape in a path displaced from the path of the separated layer toward said rounded tape engaging means.

15. A tape dispensing device according to claim 14 which comprises further a brake post mounted on said housing and accessible to finger pressure from outside 70 said housing, said post being located to have said previously separated layer of tape and adjacent portion of unseparated tape pass over it in exposure to finger pressure prior to being received by said guide means.

16. A tape dispensing device according to claim 14 which comprises further a brake plate mounted on said

housing and a braking flange mounted on said housing in normally outwardly spaced relation from said brake plate, said brake plate and said braking flange being located to have said previously separated layer of tape and adjacent portion of unseparated tape pass between them prior to being received by said guide means, and said braking flange being resiliently deflectable toward said brake plate to press and hold said previously separated layer of tape and adjacent portion of unseparated tape thereagainst.

17. A tape dispensing device according to claim 16 in which said braking flange is formed integrally with said housing, and is resiliently deflectable toward said brake plate under finger pressure.

18. A tape dispensing device according to claim 16 in which said brake plate is characterized by a hollowed region and said braking flange is characterized by an enlarged portion configured and disposed to fit closely within said hollowed region upon said braking flange being deflected toward said brake plate.
